UNITED STATES PATENT OFFICE

JOHN S. HOBSON, OF CHICAGO, ILLINOIS, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed July 18, 1925. Serial No. 44,600.

My invention relates to railway traffic controlling apparatus, and particularly to apparatus of the type comprising automatic apparatus located on the train for controlling the brakes and means located partly in the trackway and partly on the train for controlling such automatic apparatus.

One feature of my invention is the provision, in a system of the type described, of means operating independently of the speed of the train and of traffic conditions for actuating the automatic apparatus at successive points in the trackway to cause an automatic application of the brakes unless the engineman takes appropriate steps to prevent such automatic brake application at each such point.

I will describe two forms of railway traffic controlling apparatus embodying my invention, and will then point out the novel features thereof in claims.

In the accompanying drawing, Fig. 1 is a diagrammatic view showing the trackway portion of one form of railway traffic controlling apparatus embodying my invention. Fig. 2 is a view showing one form of train carried apparatus suitable for co-operation with the trackway apparatus illustrated in Fig. 1 and also embodying my invention. Figs. 3 and 4 are views illustrating the trackway portion and the train carried portion respectively of another form of railway traffic controlling apparatus embodying my invention.

Similar reference characters refer to similar parts in each of the several views.

Referring first to Fig. 1, the reference characters 1 and 1^a designate the track rails of a stretch of railway track, over which traffic normally moves in the direction indicated by the arrow. These track rails are divided, by means of insulated joints 2 or otherwise, into a plurality of successive track sections, A—D, D—E, etc., and each track section is provided with a trackway signal designated by the reference character S with an appropriate distinguishing exponent. As here shown each such signal is located adjacent the entrance end of the corresponding track section. Each signal S is controlled, by

means forming no part of my present invention, in accordance with traffic conditions in advance.

Located at intervals along the trackway are a plurality of traffic governing devices, each of which, in the form here shown, is a fixed inert ramp designated by the reference character R with a suitable exponent, one of these ramps being located adjacent the entrance to each track section.

Referring now to Fig. 2, the train carried apparatus comprises a shoe 3 supported by the frame 82 of the locomotive and so disposed as to successively engage the ramps R as the train proceeds along the stretch of track shown in Fig. 1. The shoe 3 controls a contact member 6 co-operating with two fixed contact points 5 and 7. A spring 4 normally holds the shoe 3 in its lower position in which contact 5—6—7 is closed. When the train passes one of the ramps R, however, the shoe 3 is lifted, by engagement with the ramp, to open the contact 5—6—7.

Located on the train is a main relay G and a slow releasing relay K, and these relays control a magnet valve V which is arranged to apply the brakes when de-energized. The reference character J designates a manually operable releasing switch which is so located on the train as to be accessible only when the train is at rest. This releasing switch comprises two contacts 25 and 28. Under normal conditions contact 25 is open and contact 28 is closed, but when the engineman operates the releasing switch, contact 28 is opened and contact 25 is closed.

A manually operable controller Q is also located on the train in such position that the engineman may close the circuit controller without leaving his usual position in the cab. This circuit controller comprises a dash pot 61 containing a piston 62 which enters the dash pot with very small clearance. Rigidly attached to piston 62 is a contact 64 and a second contact 13 is connected with contact 64 by means of a coil spring 65. The contact 13 is arranged to be manually operated by the engineman. Under normal conditions a spring 63 urges piston 62 to an upper position in which contact 64 is closed and contact

13 is open. When the engineman closes contact 13, spring 65 is extended and moves piston 62 downwardly against the bias of spring 63. The piston 62 moves slowly in the dash 5 pot 61 however, and a time interval therefore elapses after the closing of contact 13 and before the opening of contact 64. When contact 13 is released it immediately opens, and contact 64 again closes. It will therefore 10 be plain that the engineman can close contact 13 for a brief interval, and then reopen this contact, without causing contact 64 to open, but that if contact 13 is permanently held closed, contact 64 will be opened and re- 15 main open.

The main relay G is normally maintained in its energized condition over a stick circuit which may be traced from terminal B of a suitable source of energy not shown in the 20 drawing, through wire 5^a, contact 5-6-7 controlled by shoe 3, wire 8, front contact 9 of relay G, wires 10 and 11, winding of relay G, and wire 12 to terminal C of the same source. Slow releasing relay K is also nor- 25 mally energized over a stick circuit which passes from terminal B, through wire 16, front contact 17 of relay G, wires 18 and 19, front contact 20 of relay K, wires 21 and 22, winding of relay K and wire 23 back to ter- 30 minal C. The magnet valve V is provided with a circuit which may be traced from terminal B, through wire 27, contact 28 of releasing switch J, wire 29, front contact 30 of relay K, wire 31, winding of valve V, wire 35 32, contact 64 of circuit controller Q and back to terminal C. It will be clear from the fore- going that when the shoe 3 is in its normal position, and relays G and K have previously become energized, these relays are kept ener- 40 gized over their stick circuits, and valve V is energized to prevent an automatic brake application. I will now assume that the train passes point A in Fig. 1 and that the engineman takes no action. When the shoe 45 3 strikes ramp R^A, contact 5-6-7 is opened. As soon as the train has passed the ramp R^A, the shoe 3 returns to its original position, thereby reclosing contact 5-6-7, but the brief opening of this contact interrupts the 50 stick circuit for relay G which relay imme- diately opens. The de-energization of relay G opens its own front contact 9 so that when the shoe 3 returns to its original position the reclosing of contact 5-6-7 will not complete 55 the stick circuit for relay G. Relay G will therefore remain in its de-energized condition. The opening of front contact 17 of relay G interrupts the stick circuit for relay K which then commences to open. Due to the slow re- 60 leasing characteristics of relay K, however, a time interval elapses after the opening of front contact 17 of relay G and prior to the opening of the front contacts of relay K. At the expiration of this time interval front con- 65 tact 30 of relay K opens and interrupts the

circuit for the magnet valve V, thereby caus- ing an automatic application of the brakes.

Relay G is provided with a pick-up circuit controlled by circuit controller Q. This pick- up circuit passes from terminal B, through 70 wire 14, contact 13 of circuit controller Q, wires 15 and 11, winding of relay G and wire 12 back to terminal C. By closing the contact 13, therefore the engineman can energize relay G. It follows that if the engineman holds 75 contact 13 closed during the time interval that contact 5-6-7 is open when the shoe 3 is engaging a ramp R, relay G will not be de-energized because energy will be supplied 80 to this relay over its pick-up circuit, even though its stick circuit is opened by the shoe 3. Furthermore, if relay G is actually de-energized by the opening of contact 5-6-7, contact 13 being open, the engineman can sub- 85 sequently restore relay G to its energized con- dition by operating the circuit controller Q. To be effective, this acknowledgment, that is, the operation of circuit controller Q must be performed before relay K opens its front con- 90 tacts. But if contact 13 is held closed for too long a time, contact 64 will open, as herein- 95 before explained, thereby opening the circuit for valve V, and causing a brake application. If the front contact 20 of relay K becomes 100 open, this relay will remain in its de-ener- 105 gized condition even though contact 17 of relay G is again closed. It will be manifest that if an automatic application of the brakes actually occurs due to de-energization of mag- net valve V, operation of circuit controller Q 110 will not be effective to release the brakes.

The relay K is provided with a pick-up cir- 115 cuit which passes from terminal B, through wire 16, front contact 17 of relay G, wires 18 and 24, contact 25 of releasing switch J, wires 120 26 and 22, winding of relay K and wire 23 back to terminal C. If, when the train passes a ramp, the engineman fails to acknowledge by operating contact 13, magnet valve V will be de-energized as has already been explained, 110 and the brakes will be applied. In order to release the brakes the engineman must first acknowledge by operating contact 13. This energizes relay G. When the train has come 115 to rest, the engineman operates releasing switch J, closing contact 25 and energizing relay K. As soon as front contact 20 of relay K closes, the stick circuit for this relay is completed and the relay is subsequently main- 120 tained in its energized condition as long as front contact 17 of relay G remains closed. The engineman then restores the releasing switch J to its original position, thereby clos- 125 ing contact 28 and opening front contact 25. The stick circuit for relay K being closed, the opening of front contact 25 has no effect upon this relay. The closing of contact 28 com- pletes the circuit for magnet valve V, ener- 130 gizing this valve, and permitting the brakes to be released. The operation of the appara-

tus as the train passes each of the succeeding ramps is the same as that just described for ramp R^A. It will therefore be plain that as the train proceeds along the stretch of track the engineman must acknowledge by operating contact 13 as the train passes each of the trackway ramps irrespective of traffic conditions in advance and irrespective of the train speed. Since one of the ramps R is located adjacent each trackway signal S the effect of this enforced acknowledgment is to forcibly call the attention of the engineman to the indication displayed by each signal as he passes it.

Referring now to Fig. 3 each track section is provided with a trackway inductor designated by the reference character H with an appropriate exponent and located adjacent the signal for the associated section. Referring also to Fig. 4 the railway train indicated diagrammatically at P carries a U-shaped magnetizable core X having two downwardly projecting legs X' and X². Leg X' is provided with a winding 34 and the leg X² is provided with a similar winding 33. When contact 13 of circuit controller Q is closed, current flows from a suitable source of energy such as a battery 35, through wire 36, winding 34, wire 37, winding of relay G, wires 38 and 43, contact 13 and wires 44 and 42 back to battery 35. Relay G then becomes energized, closing its front contacts and so completing a stick circuit from battery 35, through wire 36, winding 34, wire 37, winding of relay G, wires 38 and 39, front contact 9 of relay G, and wires 41 and 42 back to battery 35. It is plain, therefore, that having once been energized by operation of contact 13, the relay G will remain in its energized condition by virtue of its stick circuit after the contact 13 is opened. A pick-up circuit for relay K passes from a battery 45, through wires 56 and 57, contact 25 of releasing switch J, wires 58 and 52, winding of relay K, wire 51, front contact 17 of relay G, wire 48, winding 33 and wires 47 and 46 back to battery 45. When this circuit is closed relay K becomes energized, thereby closing its front contacts and completing a stick circuit for this relay from battery 45, through wires 56 and 55, front contact 20 of relay K, wires 53 and 52, winding of relay K, wire 51, front contact 17 of relay G, wire 48, winding 33 and wires 47 and 46 back to battery 45. If, therefore, relay G is energized, the operation of releasing switch J causes relay K to become energized and this relay subsequently is maintained in its energized condition over its stick circuit as long as relay G remains energized after the releasing switch J is restored to its original position.

When the switch J and circuit controller Q are in their normal positions, and when relay K is energized current flows from battery 45, through wires 56 and 66, contact 64 of cir-

cuit controller Q, wire 67, contact 28 of releasing switch J, wire 59, winding of valve V, wire 60, front contact 30 of relay K, and wires 62 and 46 back to battery 45.

Under normal conditions the stick circuits traced for relays G and K are both closed and current flows through both windings 33 and 34. These windings are so arranged that the magnetic flux created in core X by current in winding 33 opposes the flux created in this core by current in winding 34. Ordinarily however, the magnetic path traversed by this flux contains a large air gap between the legs X' and X² of the core X. Under these conditions the flux caused by one winding has substantially no effect upon the current in the other winding.

Each of the inductors H located in the trackway is provided with two upstanding legs H' and H² which are so disposed that when the train passes an inductor, the reluctance of the air gap between the legs X' and X² of the train carried core X is materially reduced by the inductor. As the train passes an inductor H, therefore, the reactance of the magnetic path of the fluxes created by windings 33 and 34 is materially reduced. The flux from winding 33 linking winding 34, is therefore increased, and an electromotive force is induced in winding 34 by this increase of flux. The electromotive force thus induced in winding 34 creates a current in the circuit of relay G which opposes the current from battery 35 so that the current in relay G is reduced to substantially zero or is reversed. Relay G therefore becomes de-energized and opens its front contacts. The opening of the front contact 9 interrupts the stick circuit for the relay G so that even after the train has passed the inductor H the relay G will remain in its de-energized condition unless the contact 13 is operated by the engineman to acknowledge the passing of a trackway inductor. The opening of front contact 17 of relay G interrupts the stick circuit for relay K. After the expiration of the time interval required for operation of this relay, its front contacts open, thereby interrupting its stick circuit and causing de-energization of magnet valve V to apply the brakes. If, however, after the de-energization of relay G and prior to the opening of the front contacts on relay K, contact 13 is operated, relay G is immediately energized, thereby restoring the circuit for relay K, and preventing an automatic application of the brakes. Similarly, if contact 13 is closed when the train passes the inductor H, relay G will be de-energized as the train passes the inductor but will be energized again as soon as core X has passed the trackway inductor H. But if contact 13 is held closed for too long a time contact 64 will open and apply the brakes by de-energizing valve V. If, on the other hand, relay G remains in its de-energized condition, due to

the engineman's failure to acknowledge, long enough for relay K to open its front contacts, the stick circuit for relay K will be opened and a subsequent energization of relay G will 5 not restore relay K to its energized condition. The brakes will therefore be applied and can not be released until the train is brought to rest and the releasing switch J is operated. If relay G is energized, the operation of the 10 releasing switch J completes the pick-up circuit for relay K and when the releasing switch J is restored to its original position magnet valve V is again energized to release the brakes.

15 It should be pointed out that the apparatus illustrated in Figs. 3 and 4 operates to enforce an acknowledgment by the engineman at the entrance to each track section independently of train speed and traffic conditions 20 exactly as in Figs. 1 and 2.

It should also be pointed out that in both forms of the apparatus herein shown and described the trackway devices, whether ramps or inductors, are all inert, that is, these 25 devices do not require the supply of energy to them to make them effective. This feature is valuable because it eliminates the possibility of a failure of the system due to an interruption in the supply of such energy to the 30 devices.

Although I have herein shown and described only two forms of railway traffic controlling apparatus embodying my invention, it is understood that various changes and 35 modifications may be made therein within the scope of the appended claims without departing from the spirit and scope of my invention.

Having thus described my invention, what 40 I claim is:

1. Railway traffic controlling apparatus comprising a train carried relay, acknowledging means under the control of the engineman for at times energizing said relay, a stick circuit for subsequently maintaining said relay in its energized condition, a plurality of inert devices located at intervals along the trackway, means on the train for co-operating with said trackway devices to de-energize said relay unless the engineman operates said acknowledging means, and automatic apparatus effective at the expiration of a time interval after said stick relay is de-energized to apply the brakes.

55 2. Railway traffic controlling apparatus comprising a first train carried relay, acknowledging means under the control of the engineman for at times energizing said first relay, a stick circuit for subsequently maintaining said first relay in its energized condition, a plurality of inert devices located at intervals along the trackway, means on the train for co-operating with said trackway devices to de-energize said first relay unless the engineman operates said acknowledging means,

a slow releasing relay, a circuit for said slow releasing relay including a front contact of said first relay, and brake applying apparatus controlled by said slow releasing relay.

In testimony whereof I affix my signature. 70
JOHN S. HOBSON.
